Filed Jan. 2, 1974, Ser. No. 430,199

Term of patent 14 years

Int. Cl. D26—06

U.S. Cl. D48—32 R

FIG. 1

FIG. 2

FIG. 3

FIG. 4

FIG. 1 is a top plan view of a combined clearance and marker lamp showing my new design.

FIG. 2 is a side elevational view of the same.

FIG. 3 is a side elevational view thereof as taken from the bottom of FIGS. 1 and 2.

FIG. 4 is an enlarged partial cross-sectional view as taken on line 4—4 of FIG. 1; the faceting is omitted from the complete side of the lens for convenience of illustration, it being understood that the lens would normally appear as shown in FIG. 3.

I claim:

The ornamental design for a combined clearance and marker lamp, as shown and described.
